US00D510505S

(12) **United States Design Patent** (10) Patent No.: **US D510,505 S**
Tranfaglia et al. (45) Date of Patent: **** Oct. 11, 2005**

(54) **EATING UTENSIL**

(75) Inventors: **Christina M. Tranfaglia**, Glenview, IL (US); **Robert L. Baittie**, Vernon Hills, IL (US); **David E. Barnard**, St. Paul, MN (US); **Richard A. Nelipovich**, Madison, WI (US); **Cory R. Boudreau**, Madison, WI (US); **Ami M. Verhalen**, Sun Prairie, WI (US)

(73) Assignee: **PACTIV Corporation**, Lake Forest, IL (US)

(**) Term: **14 Years**

(21) Appl. No.: **29/198,347**

(22) Filed: **Jan. 28, 2004**

Related U.S. Application Data

(63) Continuation-in-part of application No. 10/411,633, filed on Apr. 11, 2003.

(57) **CLAIM**

The ornamental design for an eating utensil, as shown.

DESCRIPTION

FIG. 1 is a perspective view of an eating utensil;

FIG. 2 is a top plan view of an eating utensil;

FIG. 3 is a right side elevation view of an eating utensil;

FIG. 4 is a bottom plan view of an eating utensil;

FIG. 5 is a left side elevation view of an eating utensil;

FIG. 6 is a rear elevation view of an eating utensil; and,

FIG. 7 is a front elevation view of an eating utensil.

The broken line showing of indicia is for illustrative purposes only and forms no part of the claimed design.
